A. E. HUDD

ELECTRIC RELAY

Filed June 21, 1921

FIG.1.

FIG.2.

Alfred Ernest Hudd
P. David & Davis
Attn: [unclear]

UNITED STATES PATENT OFFICE.

ALFRED ERNEST HUDD, OF LIVERPOOL, ENGLAND, ASSIGNOR, BY MESNE ASSIGNMENTS, TO AUTOMATIC ELECTRIC INC., OF CHICAGO, ILLINOIS.

ELECTRIC RELAY.

Application filed June 21, 1921, Serial No. 479,322, and in Great Britain August 22, 1919.

My invention relates to improvements in or relating to electric relays and more particularly to that type of relay employed in railway signalling systems and known as the 5 "track circuit" relay.

The usual construction of this type of relay consists of a double limbed vertical electromagnet with the armature mounted on horizontal pivots beneath it.

- 10 The armature is under gravity control and has mounted on it a number of contact fingers which are adapted to make electrical connection with fixed contacts. The armature and its associated contacts are enclosed 15 in a case and as the electro-magnets project above it, it is difficult to provide a construction which is both robust and weatherproof, which properties are most important in relays of this type.
- 20 The object of the present invention is to provide a relay which readily adapts itself to a robust and weatherproof construction while at the same time it is efficient and moreover it is cheaper to manufacture than 25 the usual constructions.

With this object in view, according to my invention a horizontal electro-magnet is employed having an armature pivoted on a horizontal axis parallel to and below the core 30 of the electromagnet.

- 35 A plate suitably shaped as to fit over the electro-magnet and fitted with terminals may be provided which plate when fitted to a box in a water tight manner forms a complete 40 cover for both the electro-magnet, the armature and its associated contact fingers as also for the fixed contacts; the result is that the whole forms a very compact, serviceable and durable track circuit relay which in addition has the electrical properties of being 45 both efficient and having a comparatively small margin between operating and release currents, a very desirable feature in this class of apparatus.

50 Further details of my invention will be understood by referring to the accompanying drawings in which:

Figure 1 shows a sectional elevation of a track circuit relay, embracing the features of 55 the present invention.

Figure 2 shows an inverted plan of the same relay with the base removed.

The relay comprises an electromagnet having a core 1, cheeks 2 of magnetic mate-

rial such as Swedish iron, secured to flanges 55 5 on a cover plate 3 by means of set screws 4. The cover plate 3 is preferably shaped so as to conform to that of the electromagnet as shown, and in addition to serving as a support for the electro-magnet it serves as 60 a support for the bracket 7 carrying the armature 8 by means of the pivot screws 6 secured to the flanges 5.

As will be seen from the figures, the armature extends the whole length of the core 65 being supported so as to be separated from the core by a small air gap so that when the electro-magnet is excited the armature is attracted and tends to turn about an axis through the pivot screws 6 parallel to the 70 core 1 of the relay. The armature is under gravity control so as to be sure of restoring and not to be subjected to the possible failure of springs or like restoring means.

One advantage of the long length armature is that there is ample room for mounting the contact members 9, four of which are shown mounted independently on the armature being insulated therefrom by insulating 75 studs, preferably made of that insulating 80 material which is known under the registered trade-mark "Galalith."

The cover 3 which is preferably rectangular as shown, has insulated terminals secured thereto which may be arranged as follows:—Four terminals 11 on the right hand side of the cover each of which is immediately behind a corresponding contact member 9, to which it is connected by a flexible connection 12; four terminals 13 on the left 85 hand side of the cover to which the contact members 9 are adapted, to make connection when the armature is attracted; two terminals 14 connected to the winding of the 90 electro-magnet and arranged one on each side of the terminals 11, and two corresponding terminals 15 on each side of the terminals 13, having projecting tongues 16 to which the outside contact members 9 normally 95 make connection.

Around the periphery of the cover is a 100 recess in which is fitted a rubber gasket 22 or its equivalent adapted to form a watertight joint when secured to a box such as shown in the drawings. This box consists 105 of a base plate 18 having four upright pillars 19 secured to its corners. These pillars have two longitudinal slots on sides

facing each other into which glass plates 20 may be fitted and cemented into position.

The cover with the apparatus mounted thereon is secured to the box by means of screws engaged with the upright pillars 19 and thereby forcing the rubber gasket 22 against the upper edges of the glass plates 20 and 21 and the pillars so that all the operated parts are thoroughly and efficiently protected. The terminals 11 and 13 and the contact members 9 are similar to those generally adopted in railway signalling apparatus of this type and the construction is clearly shown in the drawing. It will be appreciated that the combination of a horizontal electro-magnet with a horizontal armature leads to a very compact construction of track circuit relay adapted to be enclosed readily in a simple case in a weather-proof and watertight manner.

Further, by arranging the armature to move about an axis parallel to the core a very efficient relay has been evolved which armature further lends itself to being extended the length of the electromagnet and thus enabling a large number of contact members to be mounted so that they may be examined, removed, and replaced independently of each other.

The scope of the invention will be better understood by referring to the accompanying claims as it will be appreciated that details of the construction may be considerably modified without departing from the spirit of the invention.

Having fully described and ascertained the features and aspects of my invention, what I consider to be new and desire to have

protected by Letters Patent will be pointed out in the appended claims.

What I claim is:

1. A track circuit relay for railway signalling systems comprising an electromagnet having a single horizontal core, circular cheeks of magnetic material fitted on said core, a winding on said core substantially filling up the space between said cheeks, an armature curved to conform to part of the circumference of said cheeks and supported on horizontal pivots so as to extend from one cheek to the other and contact members mounted on said armature and adapted to make or break connection with fixed contact members depending upon the movement of said armature.

2. A track circuit relay comprising a box, a cover adapted to be fitted to said box in a water-tight manner, brackets extending from opposite ends of said cover, an electromagnet adapted to fit snugly in a recess in said cover between said brackets, an armature for said electromagnet, cheeks on said electromagnet, screws threaded through holes in said brackets and terminating in circular pins for engaging in circular holes in said cheeks to support said electromagnet in position and two other screws similarly threaded through said brackets and terminating in circular pins for acting as pivots and supports for said armature, and contact members on said armature adapted to make or break connection with fixed contact members supported from said cover depending upon the movement of said armature.

In testimony whereof I affix my signature.

ALFRED ERNEST HUDD.
